UNITED STATES PATENT OFFICE.

JAMES D. OGDEN, OF CRAWFORD, TEXAS.

RAILWAY-TIE.

1,023,956.

Specification of Letters Patent.

Patented Apr. 23, 1912.

Application filed May 31, 1911. Serial No. 630,511.

To all whom it may concern:

Be it known that I, JAMES D. OGDEN, a citizen of the United States, residing at Crawford, in the county of McLennan and 5 State of Texas, have invented certain new and useful Improvements in Railway-Ties, of which the following is a specification.

My invention relates to new and useful improvements in railway ties. 10 The objects of my invention are to provide a railway tie which is economical, practical and of universal application to all styles of rails, both of trolley and steam roads. And further objects are to provide 15 a composite railway tie which is durable, and easy of adjustment to the road bed without removing the rail and to which rails are easily applied, and at the same time of yielding construction as will permit the 20 necessary elasticity and spring of the rails.

I accomplish these objects by means of the device illustrated in the accompanying drawings, in which,

Figure 1 is a longitudinal sectional view 25 of the tie showing the rail in place. Fig. 2 is a perspective view of the tie with the plates in position ready for the insertion of the rails.

Similar figures refer to similar parts 30 throughout the several views.

Referring specifically to the drawings, 1 are sectional ends of the ordinary railway rail, and 2 is a composite tie of suitable dimensions, composed of cement or some simi- 35 lar material, in which are to be embedded the rail plates, as hereinafter mentioned.

3 are metallic plates, of convenient di- 40 mensions, which are bent or pressed at right angles, as at 4, forming a straight or main end portion, 5, which is embedded longitudinally flatwise near the end of the tie 2 at a point to accommodate the rails 1, as they are adjusted to the tie for use, as hereinafter described. Two of these plates are 45 formed with double elbows and two with a single elbow, as herein specified, and are to be embedded in the tie 2 while in the process of construction and forming, and set in such manner that the main end portion 5, of the 50 outer plates extend outwardly and the inner plates inwardly a suitable distance to give strength to the said plates.

The plates formed with a single elbow have a perpendicularly extending arm, 6, 55 reaching slightly beyond the surface of the tie 2 when embedded therein. One inner

and one outer arm, as at 7, positioned at opposite ends of the tie 2 extend perpendicularly a suitable distance to engage the flanges 8 of the rails 1, in the use of the device. 60 After the rail is laid these perpendicular arms 7 are conveniently bent or pressed, as at 7', at right angles over and engaging the flanges 8 of the rails 1, holding the same firmly to the tie. The other plates are 65 formed with dual elbows, as at 9, forming at the ends thereof the arms 10, which extend parallel to the tie 2, and a sufficient distance above the same to permit the flanges 8 of the rails 1 to be inserted thereunder, 70 and thus coöperating with arms 7 in retaining the rails securely against the said tie.

In the use of the device the flanges 8 of the rails 1, are to be inserted under the arms 10, and pressed or driven back firmly into 75 the elbow thereof, when the arms 7 are forcibly bent by hammer or other convenient means, upon the opposite flange, thereby securing the rail securely to the tie.

To remove the rail or tie the arms 7 are 80 to be conveniently bent or pressed back into a perpendicular position and the flanges 8 forced from under the arms 10, when the tie may be taken out without removing the rail, or the rail may be taken out without 85 disturbing the ties. With this device, ties may be removed with ease and rapidity without interfering with the rail.

In the use of the device the stationary arms 10 are preferably constructed of 90 heavier material than the arms 7, which construction gives strength to the former and elasticity to the latter.

Having described my invention, what I claim and wish to secure by Letters Patent 95 is as follows:

1. A device of the character described, consisting of a cement or like material, railway tie, and a plurality of metallic plates bent or pressed at right angles, one end 100 thereof embedded longitudinally therein, the other end forming an arm extending vertically thereto and adapted to adjustment on corresponding sides of parallel rails and to be bent in engagement with the 105 flanges thereof; and a plurality of plates provided with elbows and an arm adapted to extend over the flange of a rail opposite the hereinbefore mentioned plates and in coöperative engagement therewith, substan- 110 tially as and for the purposes set forth.

2. A railway tie consisting of cement or

like material and a plurality of metallic plates bent or pressed at right angles, one end thereof embedded longitudinally there-in, the other end forming an arm extending vertically thereto and adapted to adjustment on corresponding sides of parallel rails and to be bent in engagement with the flanges thereof; and a plurality of plates provided with elbows and an arm adapted 10 to extend over the flange of a rail opposite

the hereinbefore mentioned plates and in coöperation with the same, substantially as set forth.

In testimony whereof I affix my signature in presence of two witnesses.

JAMES D. OGDEN.
